Patented Mar. 11, 1913.

UNITED STATES PATENT OFFICE.

MICHAEL PAPA-FEDOROFF AND VLADIMIR SCORCELLETTI, OF ST. PETERSBURG,
RUSSIA.

FUEL-SPRAY DIFFUSER.

1,055,789.

Specification of Letters Patent. Patented Mar. 11, 1913.

Application filed December 30, 1911. Serial No. 868,756.

To all whom it may concern;

Be it known that we, MICHAEL PAPA-FEDOROFF, mechanic, and VLADIMIR SCORCELLETTI, engineer, both of 6 Rotte No. 15, 5 St. Petersburg, Russia, have invented a certain new and useful Improved Fuel-Spray Diffuser, of which the following is a specification.

This invention relates to a device for spraying liquid fuel into the furnace of steam boilers and the like. Spray diffusers have already been proposed in which the fuel is diffused by means of compressed air or by steam, or in other devices the fuel is 10 conveyed by the pressure of air or steam and the diffusion is obtained by directing the fuel-jet against a metallic tongue or by the employment of the so-called Herz-spiral. These devices have, however, the disadvantage of incompletely diffusing the fuel, producing a noise and our invention has the 15 purpose of removing these disadvantages by providing the diffuser with two nozzles which are arranged at a suitable angle with regard to each other, the arrangement being 20 such that the two jets of fuel leaving the nozzle are forced into one another. A perfect and noiseless spraying of the fuel is thus 25 obtained.

30 In the accompanying drawings two forms of carrying out our invention are shown.

Figure 1 is a longitudinal section, and Fig. 2 shows a part of the diffuser in side elevation, while Fig. 3 is a longitudinal section 35 of a modified form. Fig. 4 a sectional view taken on the line A—B Fig. 3, and Fig. 5 a plan view of the modified form.

The diffuser consists of a body 1 which by means of a tube 2 is connected to the nozzle-head 3 by means of an interposed member 8. A cylinder 5 having openings 4 is provided 40 within the said tube 2, and is pressed against the member 8 by means of the threaded end portion or lid 6.

45 In order to prevent leakage and to insure a perfect fitting upon each other of the fuel-passages in the two members 5 and 8, the end 7 of the tube 5 is conical and fits exactly 50 into the conical seating arranged in the interposed member 8.

Two passages 9 are provided in the nozzle head 3 and their axes are arranged so as to cross each other a short distance from the nozzle end at the point 10. These passages

are tapered so as to be of less cross sectional 55 diameter at the end of the nozzle and apart from this, are extended right through the nozzle head in order to enable easy cleaning of the same in case the passages should get blocked up, and after the closing screws or stoppers 11 have been removed. A wire netting or sieve 12 surrounds the inner tube 5 and serves as a filter for the liquid fuel.

The diffuser operates in the following manner: The fuel is conveyed under pressure through the opening 13 in the body 1 into the annular chamber 15 and enters the interior of the tube 5 through the filter 12 and openings 4, after which it passes through the passages 16 and 9, 9, where it leaves the 65 nozzle in the form of two colliding thin jets. A collision of such jets is perfectly noiseless. On account of the described construction of the filter, its surface is such a large one that local interruptions of the same by impurities 70 does not affect the working of the device.

In cases where the boiler is under exceptional stress so that it becomes necessary to introduce an additional quantity of air in order to obtain an economical combustion of 80 the fuel, which particularly is the case if mixed fuel is used (naphtha and coal) as on battle-ships for instance, it is advantageous to provide the diffuser with a separate air flue into which air under pressure is introduced. The modified form of our invention as shown in Figs. 3 to 5 is specially adapted 85 to answer this purpose. The various parts of the diffuser are substantially similar to those shown in Figs. 1 and 2, with the difference, however, that the body 1' is provided with an air inlet 17 and that the tube 2' is surrounded by a cylinder 18. The interposed member 8' has a number of bores 19 which terminate in the annular chamber 90 20 from which chamber the air is sucked through a passage 21 into a channel 22, arranged vertically to the passage 21. The channel 22 communicates with a slot 23, which is positioned adjacent the ends of the 95 100 passages 9.

The tubes 2 and 5 are preferably not connected directly with the nozzle 3 so that if the nozzle is damaged it may be removed and another nozzle put in its place without 105 taking the device apart.

Having now particularly described and ascertained the nature of our said invention

and in what manner the same is to be performed, we declare that what we claim is:—

1. In a device for spraying liquid fuel, a nozzle having two passages, the ends of 5 which are inclined toward one another, a fuel tube communicating with said passages and provided with an opening for the introduction of fuel, said tube being provided with a removable end portion, a connecting 10 member interposed between said nozzle and said fuel tube, a perforated tube positioned within said fuel tube and having one end engaging said connecting member and its other end engaging said end portion, and a filter 15 surrounding said perforated tube.
2. In a device for spraying liquid fuel, a nozzle having two passages, the ends of which are inclined toward one another, a

fuel tube communicating with said passages and provided with an opening for the introduction of fuel, a connecting member interposed between said nozzle and said fuel tube, a perforated tube positioned within said fuel tube, a filter surrounding said perforated tube, and an air tube surrounding said fuel 25 tube, said air tube communicating with an opening positioned adjacent said passages.

In testimony, that we claim the foregoing as our invention, we have signed our names in presence of two subscribing witnesses.

MICHAEL PAPA-FEDOROFF.
WLADIMIR SCORCELLETTI.
